United States Patent Office

Des. 220,448
Patented Apr. 13, 1971

220,448

VEGETABLE CONTAINER OR THE LIKE

James B. Swett, Barrington, R.I., and Sidney Z. Smith,
Worcester, Mass., assignors to Dart Industries, Inc.,
Los Angeles, Calif.

Filed Jan. 28, 1970, Ser. No. 21,117

Term of patent 14 years

Int. Cl. D7—01

U.S. Cl. D44—1

FIG. 1

FIG. 4

FIG. 2

FIG. 3

FIG. 1 is an exploded perspective view of a vegetable container showing our new design;

FIG. 2 is a top plan view with the cover removed;

FIG. 3 is a bottom plan view; and,

FIG. 4 is a cross-sectional side view with the cover assembled on the container.

We claim:

The ornamental design for a vegetable container or the like, substantially as shown.
